US00D741170S

(12) **United States Design Patent**
Thurin et al.

(10) **Patent No.:** **US D741,170 S**
(45) **Date of Patent:** **** Oct. 20, 2015**

(54) **CONTAINER**(71) Applicant: **S.C. Johnson & Son, Inc.**, Racine, WI (US)(72) Inventors: **Matthew N. Thurin**, Wauwatosa, WI (US); **Rishabh Singh**, Milwaukee, WI (US); **Christopher M. Wlezien**, Chicago, IL (US); **Peter I. Capraro**, San Francisco, CA (US); **Allan Freas Velzy**, Boston, MA (US)(73) Assignee: **S.C. Johnson & Son, Inc.**, Racine, WI (US)(***) Term: **14 Years**(21) Appl. No.: **29/461,250**(22) Filed: **Jul. 19, 2013**(51) LOC (10) Cl. **09-03**

Primary Examiner — Robert M Spear
Assistant Examiner — Kendra L Hamilton(57) **CLAIM**

The ornamental design for a container, as shown and described.

DESCRIPTION

FIG. 1 is a top perspective view of a container showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view thereof.
